UNITED STATES PATENT OFFICE.

SEWALL THOMAS JEFFERSON BYAM, OF TRENTON, NEW JERSEY, ASSIGNOR
TO THE TRENTON WATCH COMPANY, OF SAME PLACE.

MANUFACTURE OF WATCH-CASES.

SPECIFICATION forming part of Letters Patent No. 424,048, dated March 25, 1890.

Application filed December 29, 1888. Serial No. 294,949. (No model.)

To all whom it may concern:

Be it known that I, SEWALL THOMAS JEFFERSON BYAM, of Trenton, in the county of Mercer, and in the State of New Jersey, have invented certain new and useful Improvements in the Manufacture of Watch-Cases; and I do hereby declare that the following is a full, clear, and exact description thereof, reference being had to the accompanying drawings, in which—

Figure 1 is a perspective view of the blank used for forming a case-back. Figs. 2 and 3 are like views of opposite sides of the same after having passed through the first operation. Figs. 4 and 5 are perspective views of said blank after having passed through the second swaging operation. Figs. 6 and 7 are like views of the same after having been operated upon by the trimming-dies, and Figs. 8 and 9 are perspective views of said blank after completion by the action of the final swaging-dies.

Letters of like name and kind refer to like parts in each of the figures.

In the manufacture of watch-cases it has heretofore been customary to solder the projecting lip, which forms a thumb-piece, to or upon the edge of a case-back, which operation not only caused a considerable expense, but was difficult to perform so as to conceal the joint and solder.

The object of my invention is to remedy the defects named; and to such end such invention consists in the method employed for forming a case-back with the thumb-piece integral with and constituting a part of the same, substantially as and for the purpose hereinafter specified.

In the carrying of my invention into practice a disk A is cut from a sheet of metal by any desired means, and is then subjected to the action of dies which give to it a cup-shaped form with an outward-projecting peripheral flange a, as shown in Figs. 2 and 3.

The blank A is next subjected to the action of other dies, which at one side compress the flange a, so as to form in relief upon the outer face of the same a thumb-piece a', (shown in

Figs. 4 and 5,) after which said blank is passed through other dies that remove nearly all of said flange and trim the surplus metal from around said thumb-piece, as seen in Fig. 6 and 7. The blank is now completed by subjecting it to the action of other dies which operate to give the edge a² upon the inner side a plane form, to extend the curve of the outer face inward to such edge, and to shape and define the thumb-piece a'.

Each of the operations described, except the third, is necessary and usual in forming a case-back without a thumb-piece, so that the only expense involved in the production of the latter is the dies and time required for such operation. It will be obvious that the case-back thus constructed will be stronger and will present a better appearance than would be practicable if the thumb-piece was constructed separately and afterward attached thereto, and that the single additional operation necessary by my method will involve but a fraction of the expense heretofore required in forming, attaching, and finishing such part. It will also be obvious that the principle of operation will be the same whether a case-back, case-front, or glass-bezel are formed.

Having thus described my invention, what I claim is—

The method of forming a thumb-piece upon and integral with a case-back, which consists, first, in giving to a blank disk a cup shape with a peripheral flange, next in impressing upon such flange the form of the thumb-piece, next in removing the surplus metal from around the blank and thumb-piece, and, finally, completing the combined case-back and thumb-piece by means of dies, substantially as and for the purpose specified.

In testimony that I claim the foregoing I have hereunto set my hand this 26th day of November, 1888.

SEWALL THOMAS JEFFERSON BYAM.
